US0D1094771S

(12) **United States Design Patent** (10) **Patent No.:** **US D1,094,771 S**
(45) **Date of Patent:** **** Sep. 23, 2025**

(54) **CHROMATOGRAPHY CASE**

(71) Applicant: **DIONEX CORPORATION**,
Sunnyvale, CA (US)

(72) Inventors: **Gary L. Gleave**, Pleasanton, CA (US);
Mrinal K Sengupta, Union City, CA (US); **Michael J. Silvers**, Daly City, CA (US); **Andres R. Honegger**, Pleasanton, CA (US); **Kerry Prowse**, Hayward, CA (US); **Kevin Shin**, San Diego, CA (US)

(73) Assignee: **DIONEX CORPORATION**

(**) Term: **15 Years**

(21) Appl. No.: **29/876,158**

(22) Filed: **May 17, 2023**

(51) LOC (15) Cl. **24-02**

(52) U.S. Cl.

USPC **D24/232**

(57) **CLAIM**

The ornamental design for a chromatography case, as shown and described.

DESCRIPTION

FIG. 1 is a front perspective of our new chromatography case;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dash-dot-dash broken lines represent boundaries of the claimed design and form no part of the claimed design. The dash-dash broken lines illustrate environmental subject matter that forms no part of the claimed design.

1 Claim, 8 Drawing Sheets
